The Steel Network, Inc., BridgeClip (2019).

Primary Examiner — Calvin E Vansant*Assistant Examiner* — Benjamin L. Gray(74) *Attorney, Agent, or Firm* — Notaro, Michalos & Zaccaria P.C.(57) **CLAIM**

The ornamental design for a clip, as shown and described.

DESCRIPTION

FIG. 1 is a top, front, left isometric view of a clip showing our design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

Throughout the drawings, broken lines denote boundaries that form no part of the design to be patented.
